WASTEBASKET

Edward E. Heck, Berwyn, Ill., assignor to Republic Molding Corporation, Niles, Ill., a corporation of Illinois

Filed Oct. 19, 1966, Ser. No. 4,339

Term of patent 14 years

(Cl. D49—30)

FIG. 1

FIG. 2

FIG. 4

FIG. 3

FIG. 5

FIG. 1 is a front elevational view of a wastebasket embodying my new design;

FIG. 2 is a rear elevational view;

FIG. 3 is a side elevational view, the opposite side being the same in appearance;

FIG. 4 is a top plan view; and

FIG. 5 is a bottom plan view thereof.

I claim:

The ornamental design for a wastebasket, substantially as shown and described.
